HAND MARKING AND PRINTING MEANS

Application filed April 21, 1927. Serial No. 185,541.

The present invention relates to hand marking and printing means and has for its object to provide improved means of this class for use with movable type, stencils or stamps which is simple in construction, highly efficient in service, convenient to operate and comparatively inexpensive to manufacture.

A further object of the invention is to provide an improved hand printing or stamping device including a T-square, straight edge or any suitable form of guide bar, having means thereon adapted to serve both as guiding and positioning means for movable type, stamps or the like to facilitate rapid marking or printing of signs, advertisements, symmetrical borders and the like.

To these and other ends the invention resides in certain improvements and combinations of parts, all as will be hereinafter more fully described, the novel features being pointed out in the claims at the end of the specification.

In the drawings:—

25 Figure 1 is a plan view illustrating one embodiment of the invention with a portion of a drawing board shown to illustrate its use;

Figure 2 is a side elevation of the same;

Figure 3 is a sectional elevation taken on 30 line 3^a of Figure 1;

Figure 4 is a front elevation of the type holder shown in Figure 1 drawn to an enlarged scale;

Figure 5 is a transverse section taken on 35 line 5^a—5^a of Figure 4;

Figure 6 is a perspective view illustrating one form of type block employed for use with the holder shown in Figures 1 and 2;

Figure 7 is a fragmentary plan of a portion of the T-square to which is shown applied a slightly different type block holder from that shown in Figure 1; and

Figure 8 is a perspective view of the type block shown in Figure 7.

45 Similar reference numerals throughout the several views indicate the same parts.

The invention illustrated in the drawings embodies an improved hand printing or marking device adapted for use by merchants or others selling various classes of goods. It

is particularly advantageous for use by department stores, restaurants, drug stores and in fact all stores and merchandizing establishments having goods to sell or by individuals desiring to display advertising or other signs for various purposes.

With the present device signs, cards or display sheets of any desired size can be quickly and neatly printed or produced without the expense incurred or the time lost by turning the work over to a printing establishment. The device can be used by the average individual for printing signs, notices and the like and affords efficient means which can be conveniently used with comparative- 65 ly little effort or expense. It permits the space required for any given word, sentence or group of letters or characters to be easily figured whereby it is possible to rapidly determine the margin to allow and also the 70 amount of paper, cardboard or other material necessary to obtain for any given display or sign.

Referring to the drawings, 10 represents a portion of a drawing board on which is 75 disposed a sheet of paper, cardboard or the like indicated at 11, which may be conveniently held in place by a suitable number of thumb tacks, one of which is shown at 12, or in case relatively thick material is used 80 the board of course would not necessarily be required.

A bar, straight edge or the like, is indicated at 13 and preferably constitutes the blade of a T-square which is employed for 85 use in a manner hereinafter described. The T-square has a head 14 to which the blade is connected by a thumb screw 15 threaded at one end into a boss 16 on the bottom of the blade and having a head 17 for turning the 90 screw to clamp the blade at any desired angle upon the head. Both the head and blade of the T-square are preferably made of metal and the head is strengthened by a downwardly turned flange 18 which is adapted to engage the side of the drawing board in the usual manner. The blade or bar 13 is provided preferably at its front edge with an upstanding flange 19 which is serrated or otherwise constructed to form a series of uni- 100

formly spaced notches 20 with corresponding abutments or projections 21 provided for a purpose which will appear hereinafter and numbered in the present instance from 1 to 80 inclusive, as shown in Figure 2. The 5 blade is also provided, preferably at its rear edge, with a scale or graduations indicated at 22 which correspond in number and are spaced the same distance apart as the abutments 21. The spaces between the graduations are preferably aligned with the lugs or projections 21 on the flange 19 of the blade. The head 14 of the T-square is also provided with a scale or graduations, indicated at 23, 10 which are spaced a definite distance apart. These spacings may be of greater or less width or equal to the spacings of the scale at the back edge of the T-square, depending upon the proportions desired between the 15 height and width of the letters or characters 20 to be printed.

Mounted upon the blade of the T-square is a holder indicated generally at 24, adapted to form a guide for the type block, one 25 of which is indicated at 24^a. The holder is in the form of a slide which is slotted longitudinally at 25 to receive the upstanding flange 19 of the T-square. The slide or holder is provided on opposite sides of the 30 slot 25 with front or rear portions 26 and 27, the former being preferably adapted to engage the front side of the flange 19 and the latter the back side thereof, the portion 27 being also adapted to engage the upper face 35 of the bar or T-square blade 13.

The holder 24 carries a laterally projecting finger or index member 28 for cooperation with the scale at the rear edge of the T-square to facilitate spacing of the type 10 block and the formation of the letters or characters to be printed or marked upon the sheet 11. The slot 25 of the holder is preferably made slightly deeper than the height of the flange 19 so that the extremities of the 15 abutments or projections 21 will not engage the holder, whereby the entire weight of the latter may be carried by the portion 27 thereof resting upon the blade as shown in Figure 3. As a means for locating and holding the slide upon the T-square, I preferably extend a hardened steel pin 29 transversely through the latter so that it will rest in the notches 20 of the flange 19 in engagement with the abutments 21 to prevent slipping or 20 accidental displacement of the slide while in type-holding position. While I prefer to use a hardened steel pin for this purpose it will be understood that one or more lugs or projections may be formed upon the holder for engagement within the notches to maintain the holder in adjusted position. Movement of the holder longitudinally of the T-square may be easily effected and during such movement the pin 29 will easily ride over the 25 inclined faces of the teeth from one notch

to another without removal of the holder from the flange 19. If preferred, the holder may be lifted entirely clear of the flange 19 and repositioned thereon at whatever point desired.

The front face of the holder is recessed at 30 and at the bottom of the recess two notches 31 and 32 are provided which are adapted to receive the teeth or projections 33 and 34, respectively, of a lug 35 formed on the back 70 side of the type block 24^a, as best shown in Figure 6. The length and thickness of the lug preferably corresponds closely to the length and width of the recess 30 in the holder so that the lug will fit snugly within the recess and prevent rocking or tilting of the type block when moved into printing position upon the sheet 11. The type is thus guided by the holder so that it will be moved into contact with the sheet at the proper angle whereby the distribution of the ink or other printing medium will be uniformly applied to the surface of the paper.

It will be noted that the teeth 33 and 34 on the type block are shaped to fit the notches 20 of the T-square so that if desired the type blocks may be used either by positioning them upon the holder or directly upon the notched flange of the T-square.

The modified form of holder 36 shown in Figure 7 is the same as that shown in Figure 1 except that the recess 30 and notches 31 and 32 are omitted and a forwardly projecting arm 37 provided which is disposed at a right angle to the body of the holder. With this 100 holder the type blocks 38 do not have the lugs 35 thereon but engage the holder as shown in Figure 7. The type blocks 38 are rounded preferably at the front side as indicated at 39 whereby to eliminate mistakes in positioning the blocks upon the holder. The flat back side 40 is adapted to engage the holder as shown in Figure 7 and since the rounded side 39 will not properly fit the holder the operator is not likely to make 110 the mistake of printing a letter upside down.

The type blocks may be of any preferred style and are preferably designed so that each of the same, except those containing the letters I, W and M will correspond in width 115 to two of the spacings on the scale at the back edge of the T-square which in turn correspond to the spacings of the abutments or projections 21 on the flange 19 which are numbered the same as the graduations on the blade 13. The block carrying the letter I will correspond in width to one of the spaces of the scale 22 while the blocks for the letters W and M will correspond to three of said spaces and the blocks for the remaining letters will correspond in width to two of said spaces. In the dotted line arrangement of the blocks shown in Figure 1 the letters I, N, and M are on blocks corresponding respectively to 1, 2 and 3 spacings of the 120

scale while the blocks for the letters H, U, T each corresponds in thickness to two of said spacings. It can be seen therefore that having a word or sentence of a given number of letters on blocks of a known width or having determined the letters for the longest line to be printed, the over all dimension of the blocks for said letters plus the margin to be allowed will determine the width of the sheet to be used. With this arrangement therefore it is not necessary to allow for any space between the letters when printing, it being only necessary to move the holder each time a number of spaces corresponding to the spacings for the individual blocks. For example, in Figure 7, after printing with the type block 38 of a two-space width the holder is moved two spaces to the right for the next block to be used. Likewise for each block used the holder is moved to the right a number of spaces corresponding to the width of the previously used block, except between words where one or more spacings should be allowed. With blocks of a given height having determined the number of lines of printing and the spacing between the same and allowing for sufficient margins, the height of the sheet may also be readily determined.

The height of the blocks shown preferably corresponds to five of the spacings on the head of the T-square, these spacings being preferably made smaller than those on the blade. The relative proportions of the spacings on the two scales may be varied to afford the use of blocks containing letters or characters of any desired height and width.

In arranging the printing upon the sheet, after having decided upon the height of the blocks containing the letters and the spacing between the lines of printing, guide lines 41 are first drawn at the correct distances apart, in the present instance six spacings on the scale 23, being lightly drawn with a pencil by moving it against the front edge of the T-square. Having decided to use type blocks five spaces high and to employ one space between the lines of printing, as many of the guide lines 41 as are needed should be drawn 6 spaces apart before any printing is done. Thereafter in printing, the T-square is first set with its front edge in registry with the guide line 41 and for example, if it is desired to print the letters H, U and T the holder is positioned upon the T-square at the desired point and the letter H is printed. The holder is then moved to the right a distance of two notches on the T-square and the letter U is printed and is again moved two notches to the right, after which the letter T is printed. In all operating positions of either holder, the right hand edge of the pointer will be aligned with one of the graduations on the scale and if it is desired to move the holder three spaces this can easily be done by sliding it upon the T-square

until the pointer reaches the third space to the right at which position the pin 29 will take into the correct notch of the flange 19.

When it is preferred to have the lines of printing inclined with respect to the edge of the sheet, the thumb screw may be loosened and the blade of the T-square swung to any angular position desired and clamped ready for use both in drawing parallel guide lines for the printing and for guiding the type holding slide as explained above.

Two different height letters may be used both of which would require the same spacing, the larger of the two being slightly compressed and the smaller slightly extended. This allows for bringing out prominently any portion of the printing desired. If preferred both sizes could be made open face or solid or one of each as deemed advisable. Still other sets of type or type blocks can be furnished twice the size of the above and therefore requiring twice the spacing or 6, 4 and 2 spaces for the letters M, N and I respectively, thus using the same spacing device for different size type blocks. Each size may be used to print separate colors to further bring out the desired portions with prominence whereby to vary the color scheme and to improve the arrangement of the characters.

When open face type is used different colors may be employed to fill in the impressions. Thus the effects and combinations which can be worked out are practically endless. When only one size type is used, as with present hand printing outfits, the type must be cleaned every time a different color is used, but with the present system the same color could be used on the same size or style of type, throughout.

The angular shaped notches and abutments or projections 20 and 21 may be varied in shape and size and other forms of notches and projections may be provided for regulating the position of the type holder upon the bar without departing from the spirit of invention. These may be located rearwardly of the front edge of the T-square blade and may constitute holes or recesses formed in the surface thereof or in a strip or bar attached thereto at any desired distance from the front edge of the blade.

The present device may be used for other purposes than printing signs, as for example, the marking of impressions by the use of steel stamps or the like which can be guided and spaced in the same manner as the movable type or it may be used in making symmetrical borders by the use of a series of different or like stamps or other character forming elements.

What I claim as my invention is:—

1. In hand printing means, the combination of a T-square provided with a scale, the blade of the T-square having an upstanding serrated flange and a type holder adjustable

upon the flange and provided with a portion adapted to cooperate with the serrations to maintain the holder in adjusted position upon the flange, said holder having a finger 5 extending therefrom and cooperating with the scale to facilitate spacing of the type.

2. In hand printing means, the combination of a T-square provided with an up-standing flange having a series of notches 10 formed therein and a type holder adapted to be guided by said flange and having a portion arranged to engage in the notches to maintain the holder in adjusted position, said holder having angularly disposed portions 15 adapted to receive the type whereby to facilitate use of the same.
